A. G. HEBBLETHWAITE

CIGARETTE HOLDER

Filed March 28, 1924

UNITED STATES PATENT OFFICE.

ALFRED GEORGE HEBBLETHWAITE, OF KEIGHLEY, ENGLAND, ASSIGNOR OF ONE-HALF TO GEORGE CROFT FOULDS, OF KEIGHLEY, ENGLAND.

CIGARETTE HOLDER.

Application filed March 28, 1924, Serial No. 702,532, and in Great Britain February 6, 1924.

In using a cigarette holder the removal of the unburnt or other portion of a cigarette left in said holder is often a source of inconvenience and annoyance by reason of the paper covering of the cigarette adhering firmly to the inner wall of the socket within which it has been placed. To provide means which will readily and effectively remove such adhering paper while the same means will, during the use of the cigarette holder, permit perfect freedom for the draught through the cigarette and the holder during smoking, is the object of my present invention.

To attain this object I construct a cigarette holder as hereinafter described and claimed.

Of the accompanying drawings forming a part of this specification,

Figure 1 is an elevation, showing a holder embodying the invention, the cylinder and its scraping tongues hereinafter described being in position to permit the insertion of a cigarette in the socket.

Figure 2 is a similar view to Figure 1, showing the cylinder in the position it occupies after scraping paper from the inner wall of the socket.

Figure 3 is an end elevation of the holder shown by Figures 1 and 2 as seen looking in a direction from left to right of said figures.

Figure 4 is a longitudinal section of the holder.

Figure 5 is a section on line A, B, of Figure 4.

Figures 6 and 7 are elevations illustrating a modification.

Figure 8 is a longitudinal section of the holder shown by Figures 6 and 7, with the parts in the position shown by Figure 6.

Figure 9 is a side elevation, showing the cylinder shown by Figures 1 to 5, inclusive, removed from the holder socket.

Figure 10 is an elevation showing the mouth piece portion of the holder illustrated by Figures 6, 7 and 8, in detail.

Figure 11 is an elevation showing the socket portion of the holder shown by Figures 6, 7 and 8.

In carrying my invention into effect, as shown by Figures 1, 2, 3, 4, 5 and 9, I mount within the socket portion *b* of the holder, and in contact with the inner wall *a*

of the said socket portion, a hollow cylinder or bush *c*, of resilient sheet metal, in close contact with said inner wall, the cylinder forming an unobstructed passage for smoke from the socket to the duct *d*, through the mouth piece portion *b*² of the holder. 55

This bush or cylinder *c* is arranged to slide within the socket, so that when withdrawn to its rearmost position shown by Figures 1 and 4, the end of the cigarette may be inserted in the outer part of the 60 socket. When the smoker commences to draw air through the cigarette, such air is permitted to pass unobstructedly through the cylinder *c* and through the duct *d*.

The outer end of the cylinder *c* is provided with slots *h*, subdividing said end into longitudinal resilient tongues, having scraping outer ends *c'*. The tongues are tensioned, so that they normally spring outward, as shown by Figure 9. When the cylinder is inserted in the socket, the scraping ends *c'* are pressed radially against the inner wall *a*, and are adapted to scrape therefrom any cigarette paper which may adhere thereto. 75

When the user desires to discharge or displace the end of the cigarette from its position within the socket, as when the major part of the cigarette has been consumed, he moves the cylinder *c* lengthwise within the 80 socket and towards the outer end of the holder, as shown by Figure 2.

The scraping ends *c'* of the cylinder *c* move in scraping contact with the inner wall *a*, so that any adhering paper is removed 85 from the holder when the cylinder *c* reaches the position shown by Figure 2.

The movement of the cylinder *c* within the socket is effected by the manipulation, by the user, of a projection *f* which is fixed 95 to the cylinder *c* and extends through a slot *g* in the wall of the socket portion *b*. The projection *f* in conjunction with the slot *g* acts both as means for operating or moving the cylinder *c* as well as for retaining 100 the same in position.

In the embodiment above described, the socket and mouth-piece portions of the holder form one integral part, but it is obvious that the said portions may be made in separate parts, as shown by Figures 6 to 8, inclusive, and by Figure 11.

In this latter case the socket portion *b*²

is mounted to slide on the outer end of the mouth portion b' and a projection f^2 is fixed to the mouth-piece portion and cooperates with a slot g^2 in the socket portion, in guiding and limiting longitudinal movement of the socket portion on the mouth-piece portion.

The cylinder or bush, here designated by c^2 , is shorter than the cylinder c above described, and is fixed to the outer end of the mouth-piece portion b' , as by a boss h (Figure 10) formed on the cylinder, entering a recess b^4 in the slightly reduced end of the mouth-piece portion.

15 The cylinder is provided, as before, with tensioned tongues having scraping ends c' , and adapted to spring outward against the inner wall a' of the socket portion. The inner wall a' may be tapered as shown by Figure 8, the tension of the tongues enabling the scraping ends c' to follow the taper of the wall and remove paper adhering thereto.

In each of the illustrated embodiments of the invention, the holder is provided with 25 a hollow cylinder of resilient sheet metal, which is slotted at its outer end to form a circular series of resilient tongues having scraping outer ends, the tongues being tensioned to normally spring outward, so that 30 the scraping ends are pressed radially outward against the inner wall of the socket, and are adapted to scrape off paper adhering

to said wall, whether the wall be straight or tapering.

In each embodiment the cylinder and the 35 socket are relatively movable, so that the tongues may be spaced inward from the mouth of the socket, as shown by Figures 1, 4 and 8, to leave the outer portion of the socket unobstructed for the reception of a 40 cigarette, and may be caused to scrape paper from said wall after the major portion of the cigarette has been consumed.

Such being the nature and object of my 45 said invention, what I claim is:

A cigarette holder having in its receiving socket a hollow cylinder of resilient sheet metal, open from end to end, so that it does not obstruct the passage of smoke through the holder, and slotted at its outer end to 50 form a circular series of resilient tongues, which have scraping outer ends and are tensioned to normally spring outward, so that the scraping ends are pressed radially outward against the inner wall and are adapted 55 to scrape paper therefrom, the cylinder and the socket being relatively movable, so that the tongues may be spaced inward from the mouth of the socket, to leave the latter unobstructed for the reception of a cigarette, 60 and caused to scrape paper from the inner wall after the major portion of the cigarette has been consumed.

ALFRED GEORGE HEBBLETHWAITE.
